BOX CLAMPING DEVICE

Filed April 7, 1926

INVENTOR:

EDWARD C. ANSCHUTZ

BY
Hugo A. Maerlender

ATTORNEY.

UNITED STATES PATENT OFFICE.

EDWARD C. ANSCHUTZ, OF CLEVELAND, OHIO, ASSIGNOR OF ONE-HALF TO FRANK S. GLASER AND JULIUS M. GLASER, BOTH OF CLEVELAND, OHIO.

BOX-CLAMPING DEVICE.

Application filed April 7, 1926. Serial No. 100,342.

My invention relates to improvements in means for holding the covers of paper boxes while being sealed. It has for one of its objects the elimination of machines to which 5 boxes are brought to have the covers held on under pressure to effect sealing. Another object of my invention is to supply a device which is convenient to handle, portable, and to assist substantially in a process of 10 sealing a large number of cardboard, corrugated and fibre boxes and shipping cases. A further object is to create a cheap method of satisfying the need of holding the flaps of stiff cases down until the mucilage 15 or gum paper is fixed. More specifically my invention relates to a clamp for holding down the covers of collapsible fibre boxes and shipping cases until they are sealed. While in the annexed drawings only a particular form of my invention is described and illustrated the mechanical equivalents 20 and methods by which the same results are obtained are within the contemplation of my invention.

25 In said annexed drawings:

Figure 1 shows a side elevation of the clamp in its collapsed form when not in use;

Figure 2 illustrates a side elevation of the clamp in its expanded position when it is 30 applied to a box for holding down the flaps while being sealed;

Figure 3 shows a side elevation of the clamp;

Figure 4 consists of an enlarged plan view 35 of the adjusting bolt taken on the line IV-IV, Figure 2;

Figure 5 represents an enlarged vertical section of the adjusting bolt on the line V-V, Figure 2; and

40 Figure 6 illustrates a vertical section taken on the line VI-VI, Figure 5, showing the adjusting bolt in its locked position.

Referring to the same elements by the same ordinals throughout the several views,

45 I designate a straight bar with the ordinal 1 at one end of which is pivoted the arm 2 mounted on the rivet 3 traversing the arm 2 and the bar 1. In order to present a flat surface at its lower part the arm 2 is twisted

50 through an angle of 90 degrees somewhere near its center where an eyelet 4 is riveted to the arm 2. Beneath the eyelet a finger 5 formed to make a right angle with the arm

2 at its lower intersection is riveted to the arm 2 at the points 6. On the outer side of 55 the arm 2 a handle 7 is riveted at the points 8.

The opposite end of the bar 1 is provided with indentations 10 having narrow necks 10' spaced as desired on the upper edge of 60 the bar 1 as plainly indicated in Fig. 1. An arm 2' similar to arm 2 and similarly fitted with an eyelet 4', finger 5' and handle 7' 65 riveted at the points 8' has in place of an ordinary rivet a bolt 9 held in place by the wing nut 15 as shown in Figure 5. The portion of the bolt passing through the opening 10 has its sides cut away, as is plainly shown in Figure 5. By means of the narrowed section the bolt 9 is slipped 70 into one of the indentations 10 by way of the narrow necks 10'. The nut 15 need not be removed to change from one notch to another because of the thinned section of the bolt 9. To lock the bolt in the desired notch 75 the bolt 9 is turned by means of its flat head through an angle of 90 degrees into the position shown in Figure 6 so that the bolt forms a pivot for the bar 1 and the arm 2'. 80

The arms 2 and 2' are connected by means of the spring 11 which normally tends to hold the component parts of the clamp in the position indicated in Figure 1.

When it is desired to use the clamp the 85 effective length of the bar 1 is adjusted to the length of the width of the boxes upon which the clamp or clamps are to be used. By means of the handle 7 and 7' the arms 2 and 2' are pulled outward and slipped 90 over the sides of the box 14 until the fingers come in contact with the top 12.

When a case has been loaded two of the 95 four sides are folded over, forming the surface 13. This surface is coated with mucilage and the other flaps are folded over. Because of the stiffness of new boxes the flaps tend to fly away from this position and to prevent this action until the glue is set a pair of clamps are slipped over the box as indicated in Figure 2 to hold the flaps until fast.

The clamps obviate the necessity of applying cumbersome weights or of moving 105 the boxes to a machine for sealing. With about a half-dozen pairs of clamps a con-

tinuous process of sealing can be maintained because by the time the last box is clamped and sealed the first one is fast and the clamps may be removed and used on another box.

What I claim is:

1. A box-sealing device comprising in combination a rod; an arm pivotally attached to one end of said rod; a similar arm adjustably and pivotally attached to the opposite end of said rod; resilient means affixed to both of said arms tending to bring said arms together; fingers perpendicularly fastened to the opposite inner surfaces of said arms and being on opposite sides from said rod relative to said resilient means; and handles affixed to the outer surfaces of said arms. 60
2. A box-clamping device comprising in combination a rod; an arm pivotally swinging on one end of said rod; a similar arm engaging slots with necks and situated at spaced intervals near the opposite end of said rod by means of a bolt having lateral indentations enabling said bolt to by-pass the necks of said slots and preventing egress of said bolt when the latter is rotated through an angle of 90 degrees; fingers perpendicularly fastened to the opposite inner surfaces of said arms; resilient means affixed to both of said arms intermediate the fingers and the pivoted ends and tending to pull said arms together; and handles affixed to the outer surfaces of said arms. 65
3. A box-clamping device comprising in combination a rod; an arm pivotally swinging on one end of said rod; a similar arm engaging slots with necks and situated at spaced intervals near the opposite ends of said rod by means of a bolt having lateral indentations enabling said bolt to by-pass the necks of said slots and preventing egress of said bolt when the latter is rotated through an angle of 90 degrees; fingers perpendicularly fastened to the opposite inner surfaces of said arms intermediate the fingers and the pivoted ends and tending to pull said arms together; and handles affixed to the outer surfaces of said arms. 70
4. A box-sealing device comprising in combination a rod; an arm pivotally attached to one end of said rod; a similar arm pivotally attached to the opposite end of said rod; resilient means affixed to both of said arms tending to bring said arms together; fingers perpendicularly fastened to the opposite inner surfaces of said arms and being on opposite sides from said rod relative to said resilient means; and handles affixed to the outer surfaces of said arms. 75
5. A portable box-clamping device comprising in combination a rod; an arm pivotally swinging on one end of said rod; a similar arm engaging slots with necks and situated at spaced intervals near the opposite end of said rod by means of a bolt having lateral indentations enabling said bolt to by-pass the necks of said slots and preventing egress of said bolt when the latter is rotated through an angle of 90 degrees; fingers perpendicularly fastened to the opposite inner surfaces of said arms; resilient means affixed to both of said arms intermediate the fingers and the pivoted ends and tending to pull said arms together; and handles affixed to the outer surfaces of said arms. 80
6. An adjustable box-clamping device comprising in combination a rod; an arm pivotally swinging on one end of said rod; a similar arm engaging slots with necks and situated at spaced intervals near the opposite end of said rod by means of a bolt having lateral indentations enabling said bolt to by-pass the necks of said slots and preventing egress of said bolt when the latter is rotated through an angle of 90 degrees; fingers perpendicularly fastened to the opposite inner surfaces of said arms; resilient means affixed to both of said arms intermediate the fingers and the pivoted ends and tending to pull said arms together; and handles affixed to the outer surfaces of said arms. 85
7. An adjustable box-clamping device comprising in combination a rod; an arm pivotally swinging on one end of said rod; a similar arm engaging slots with necks and situated at spaced intervals near the opposite end of said rod by means of a bolt having lateral indentations enabling said bolt to by-pass the necks of said slots and preventing egress of said bolt when the latter is rotated through an angle of 90 degrees; and fingers perpendicularly fastened to the opposite inner surfaces of said arms, said arms being drawn together by resilient means. 90
8. A box-clamping device comprising in combination a rod; an arm pivotally swinging on one end of said rod; a similar arm engaging slots with necks and situated at spaced intervals near the opposite end of said rod by means of a bolt having lateral indentations enabling said bolt to by-pass the necks of said slots and preventing egress of said bolt when the latter is rotated through an angle of 90 degrees; and fingers perpendicularly fastened to the opposite inner surfaces of said arms, said arms being drawn together by resilient means. 95
9. A box-clamping device comprising in combination a rod; an arm pivotally swinging on one end of said rod; a similar arm engaging slots with necks and situated at spaced intervals near the opposite end of said rod by means of a bolt having lateral indentations enabling said bolt to by-pass the necks of said slots and preventing egress of said bolt when the latter is rotated through an angle of 90 degrees; and fingers perpendicularly fastened to the opposite inner surfaces of said arms, said arms being drawn together by resilient means. 100
10. A box-clamping device comprising in combination a rod; an arm pivotally swinging on one end of said rod; a similar arm engaging slots with necks and situated at spaced intervals near the opposite end of said rod by means of a bolt having lateral indentations enabling said bolt to by-pass the necks of said slots and preventing egress of said bolt when the latter is rotated through an angle of 90 degrees; and fingers perpendicularly fastened to the opposite inner surfaces of said arms, said arms being drawn together by resilient means. 105

Signed by me this 20th day of February, 1926.

EDWARD C. ANSCHUTZ.
